United States Patent Office

Des. 196,613
Patented Oct. 15, 1963

196,613

BOTTLE

Richard L. Platte, Ann Arbor, Mich., assignor to The Dow Chemical Company, Midland, Mich., a corporation of Delaware

Filed Apr. 24, 1963, Ser. No. 74,597

Term of patent 14 years

(Cl. D58—8)

Fig. 1

Fig. 2

I claim:

The ornamental design for a bottle, substantially as shown and described.
